UNITED STATES PATENT OFFICE.

HALVOR G. HOMME, OF GRANITE FALLS, MINNESOTA.

MAIL-BOX.

No. 830,231.

Specification of Letters Patent.

Patented Sept. 4, 1906.

Application filed October 19, 1905. Serial No. 283,484.

To all whom it may concern:

Be it known that I, HALVOR G. HOMME, a citizen of the United States, residing at Granite Falls, in the county of Yellow Medicine 5 and State of Minnesota, have invented certain new and useful Improvements in Mail-Boxes; and I do declare the following to be a full, clear, and exact description of the invention, such as will enable others skilled in the art to which it appertains to make and use the same.

My invention relates to improvements in mail-boxes, and particularly to those adapted for use in the rural-free-delivery mail 15 service.

The object of the invention is to provide a simple, inexpensive, durable, and convenient rural-free-delivery mail-box which may be readily opened by the mail man to permit of 20 the depositing of mail therein and which when opened will prevent access to the mail that has already been deposited in the box.

With the above and other objects in view the invention consists of certain novel features of construction, combination, and arrangement of parts, as will be hereinafter described and claimed.

In the accompanying drawings, Figure 1 is a perspective view of my improved rural-free-delivery mail-box. Fig. 2 is a vertical transverse sectional view through the same, showing in full and dotted lines the opened and closed positions of the cover or lid and the tilting mail receiver or tray; and Fig. 3 is a 35 top plan view of the box with its cover or lid in its opened position.

Referring to the drawings by numeral, 1 denotes my improved rural-free-delivery mail-box, which is preferably of rectangular form, 40 as shown, with a portion of its top inclined forwardly and downwardly. The opening 2, formed by this portion of the top, is adapted to be closed by a swinging cover or lid 3, which is hinged, as shown at 4, along the top 45 edge of the front wall of the box and is of angular form in cross-section, so that when in its closed position it is adapted to close the opening 2 and covered or closed portion 5 of the top of the box. This cover or lid 3 has 50 around its edges flanges 6, and upon the flange at its outer or free edge is a longitudinally-extending bead 7, which permits the cover to be readily grasped and swung to its open position. The flange along the hinged 55 edge of the cover is adapted to engage the outer face of the front wall of the box to sup-

port the cover in its open position. (Shown in full lines in Figs. 2 and 3 of the drawings.) In the front wall of the box is formed an opening 8, which is adapted to be closed by a door 9. The latter is hinged, as at 10, and is adapted to be locked in its closed position by a lock 11 of any suitable form and construction. This door 9 has flanged ends 12 and a bead 13 along its outer or free edge. Said 65 bead 13 is adapted to enter beneath a downwardly-inclined flange 14, provided on the front wall of the box along the upper edge of the opening 8. The door 9 has along its hinged lower edge an outwardly-projecting 70 flange 15, which when the door is opened is adapted to engage the outer wall of the box to support said door in a horizontal position. The opening 8 and door 9 are provided for the removal of mail-matter from the box by the 75 owner, who has a key to the lock 11, and the opening 2 and its cover 3 are provided to permit the mailman to deposit mail into the box.

The interior of the box 1 is divided into upper and lower compartments 16 17 by a mail receiver or tray 18, upon which the mail is deposited by the mailman when the cover or lid 3 is in its open position. This receiver 18 is 80 pivotally mounted at the center of its ends 85 and the end walls of the box, so that it is adapted to tilt from a substantially horizontal position to a substantially vertical position to dump the mail deposited upon its top into the lower compartment 17 of the box. 90 The tilting of the receiver is done automatically by swinging the cover or lid 3, this being effected by a link 19, which connects the two. Said receiver 18 is of rectangular form with longitudinally-extending beads 20 provided 95 along its side edges and transversely-extending reinforcing ribs 21 upon its under side or bottom. It is pivotally mounted between the end walls of the box by a pivot-rod 22, which extends longitudinally upon its under 100 side and through the ribs 21, suitable bearings 23 being provided in the end walls of the box to receive the ends of the pivot-rod. The link 19 has one of its ends pivotally connected, as at 24, to one end of the receiver 105 and its other end similarly pivoted, as at 25, upon the inner face of the cover or lid 3, as clearly shown in Fig. 3 of the drawings.

In order to prevent access to the lower compartment 17 of the box when the cover 110 or lid is being opened and closed and the receiver 18 is tilted, the opening between the

two compartments is restricted by inclined ledges or shelves 26, and the opening 27 between them is adapted to be opened and closed by a curved guard 28, depending from one edge of the receiver. The ledges or shelves 26 extend longitudinally and project downwardly and inwardly from the inner faces of the front and rear walls of the box. The guard 28 is of segmental form and is rigidly secured to or formed upon the rear or inner side edge of the receiver, so that as the latter is oscillated said guard will open and close the space 27 between the two ledges or shelves. It will be seen that this construction will close the opening 27 whenever the lid or cover 3 is opened or is in a partially-opened position, so that access to the compartment 17 of the box is prevented, except through the opening 8 in its front wall.

20 In order to permit the owner of the box to place mail-matter therein which he desires the mailman to post, I provide upon the inner face of the cover or lid 3 a bracket 29, which is adapted to receive a removable letter holder or pocket 30, which, as shown, is of wedge shape in form. Any mail placed in this pocket will not be dumped therefrom when the cover 3 is swung to its closed position.

30 From the foregoing description, taken in connection with the accompanying drawings, the construction and operation of the invention will be readily understood without requiring a more extended explanation.

35 Various changes in the form, proportion, and the minor details of construction may be resorted to without departing from the principle or sacrificing any of the advantages of

this invention as defined by the appended claims. 40

Having thus described my invention, what I claim as new, and desire to secure by Letters Patent, is—

1. A mail-box having a downwardly-opening cover hinged at its lower side to one side 45 of the box, a mail-receiver pivotally mounted in said box, and a link connecting said receiver and cover and bearing on the wall to which the cover is hinged when the cover is opened and serving to support the cover in 50 such opened position and to also secure the mail-receiver against movement independently of the cover.

2. A mail-box having a downwardly-opening cover hinged at its lower side to one side 55 of the box, a mail-receiver pivotally mounted in said box, and a link connecting said receiver and cover and bearing on the wall to which the cover is hinged when the cover is opened and serving to support the cover in 60 such opened position and to also secure the mail-receiver against movement independently of the cover, said box having oppositely-disposed downwardly-inclined plates 65 26 below the mail-receiver and forming an opening between them, and said mail-receiver having a curved guard 28 depending from the side thereof, opposite that to which the link is connected.

In testimony whereof I have hereunto set 70 my hand in presence of two subscribing witnesses.

HALVOR G. HOMME.
